UNITED STATES PATENT OFFICE.

EZRA JUDSON BUCKNAM, OF TORONTO, ONTARIO, CANADA.

MEANS FOR PROTECTING BANKS AND THE LIKE.

Application filed November 21, 1923. Serial No. 676,196.

This invention relates to improvements in means for protecting banks and the like and more particularly to automatically operable means for preventing bank robberies by bandits and otherwise, and the objects of the invention are to provide systematic and automatic means adapted to be controlled by the officers of the bank whereby individuals doing business with the bank are unconsciously held until the business is satisfactorily completed and then permitted a free exit.

Further objects are the provision of automatically operated turnstile means in combination with means operated by the cashier or other officials of the bank, whereby an individual having business to transact with the cashier is automatically held in a compartment of the turnstile before the cashier's cage until his business is completed and then only released by the action of the cashier in operating the turnstile.

Still further objects are to provide, in addition to automatically operable and lockable turnstile means designed to be secretly controlled by an official of the bank, means also controlled by the cashier or otherwise for closing the cashier's wicket opening by itself or all the wickets in the office and the front door simultaneously.

Still further objects are the provision of economically constructed and efficient means of this character whereby the business of a bank can be carried on without any extraordinary inconvenience or interference with the conditions at present existing but by means of which it will be impossible for anyone attempting to rob the bank to get away.

With my improved means the movements of anyone doing business with the bank are practically controlled while in the bank by the officials of the bank on the other side of the counter and without the knowledge of the customers concerned.

With the foregoing and other objects in view, the invention consists essentially in the novel construction and arrangement of parts described in the present specification and illustrated by the accompanying drawings that form part of the same.

Referring now to the drawings, in which like characters of reference indicate corresponding parts in each figure,

Figure 1 is a perspective view of my improved turnstile with supplementary side wall and partitions separating it from the cashier's cage. 55

Figure 2 is a vertical section.

Figure 3 is a section on the line 3—3 of 60 Figure 2.

Figure 4 is an enlarged view of the bottom of the turnstile, showing the locking means therefor.

Figure 5 is a section on the line 5—5 of 65 Figure 4.

Figure 6 is a vertical section on the line 6—6 of Figure 5.

Figure 7 is a detail view of the automatically operable trip mechanism. 70

Figure 8 is a longitudinal section of the automatically operable trip mechanism.

In the drawings, in which an embodiment of my device is illustrated, A designates the turnstile of special construction and B the bank counter provided with the usual wicket opening therein, C. 75

Referring now more particularly to the turnstile A, this is formed in three compartments 10, 11 and 12 and is preferably, as a whole, of the usual standard circular construction provided with a suitable top 13 and a suitable bottom 14, the whole being mounted on a centre and rotatable post member 15 suitably journaled at the bottom at 16 and pivotally braced at the top at 17 by means of a bracket 18 fixedly mounted on the counter partition. 85

The bottom 14 of the turnstile is provided with a base plate 19 and mounted thereon on ball bearings 20. 90

The compartments 10, 11 and 12 are provided with curved partition walls 21, 22 and 23, the whole turnstile being constructed of any suitable material, preferably of 95 steel, and designed to readily rotate.

In order to ensure that the turnstile will only rotate in one way, I provide, on the bottom, an angle iron 24 of circular configuration extending all the way around. This angle iron is provided with a plurality of notches 25 in the lower edge adapted to engage with a pivotally mounted dog 26, thus efficiently preventing the turnstile being rotated otherwise than in one direction. 100

From the foregoing it will be seen that the novel features of my turnstile, so far, are the provision of the three compartments

separated by curved partition walls, the objects of this construction being, as shown in Figure 3, that the partitions will register in a substantially straight line with the side 5 of the cashier's cage, thus providing a space in the turnstile to register with the space of the cage opening.

In addition to these curved partition walls, it will be noted that I also provide 10 partially extending side walls 27, 28 and 29 for the compartments 10, 11 and 12. This is further to ensure that the opening in each compartment will be of sufficient dimensions 15 to register with the opening in the cashier's cage.

By means of these walls, it will be noted 20 that, as the occupant is allowed to proceed out, the wicket door of the cage will be closed until the next compartment, with another customer in it, is moved around opposite the space in the side wall therein, thus again opening communication between 25 the turnstile and the cashier.

Referring now to the means for automatically locking and releasing the turnstile, this 25 comprises a bolt-shuttle member 30 in a suitable casing 31, spring actuated by means of a spring 32 between the end of the bolt 30 and the end of the casing and designed to 30 hold the bolt in projecting position automatically. The inner end of the bolt is flexibly connected by means of a cable or the like 33 to a pivotally mounted lever 34 connected by a link or arm 35 to a push pin 36 having a coiled spring 37 wound thereon, so that, when the flat top 38 of the push pin 35 is pressed upon, the bolt 30 will be momentarily drawn inwardly.

This bolt member is adapted to engage 10 with each of a plurality of spring actuated stop members 39 carried by the turnstile for each of the several compartments, so that, as shown in Figure 5, when the turnstile reaches the bolt member 30 and the 15 stop 39 engages therewith, the turnstile is locked, as, on account of the serrated bottom edge engaging with the dog 26, it can not move backwards.

This arrangement is so developed that 50 the locking operation takes place when the opening in each compartment registers with the opening in the cashier's wicket and the occupant of the turnstile compartment is thus enabled to transact his business with 55 the cashier or other officer of the bank with privacy and despatch. When the business is finished, the cashier pushes the push pin 36 with his foot, causing the bar 30 to recede and allowing the turnstile to revolve.

60 The objects of having the stop members 39 spring actuated is to absorb the shock when these members in turn contact or engage with the locking bar 30.

When the push pin 36 is pressed and so 35 that it will not be necessary for the operator

to keep his foot on it to retain the bar 30 in withdrawn position, I provide means for automatically holding the bar 30, comprising a substantially V-shaped dog 40 pivotally mounted on the front end of the casing 70 31, the casing itself being provided with stop lugs 41 and 42 to limit the travel of the dog. This dog is adapted, as shown in Figure 7, to contact with the bar 30, which holds it in the position as shown in Figure 75 7. When the bar is moved inwardly, the dog 40 will swing, of its own weight, downwardly until stopped by the lug 42, thus closing the opening in the casing for the bar 30 and retaining the bar within the casing. 80 Then as the turnstile rotates, a block 43 on the outside lower edge thereof, of which there is one for each compartment and arranged in combination with the spring actuated stop means 39, moves over the dog 40, 85 tilting one arm of it upwardly, as shown in Figure 7, and thereby causing the other arm to move away from the opening of the bar 30, allowing it to again project, as shown in Figure 5, to engage with the stop member 90 39.

By means of this construction the bank 95 official has only to momentarily press the push pin 36 to withdraw the locking bar 30 and thus release the turnstile for rotation, the latter being again automatically locked by the mechanism described.

With my improved turnstile it will be noted that no individual can see or know what transactions are taking place between the individuals in the compartments and the bank officials and that, as previously stated, the turnstile is all the time under complete and concealed control by the bank 100 official. It will be obvious that when a 105 patron has finished a deal with the cashier, the latter will press the lever 36 thus withdrawing the bolt 30 from its engagement with the lug 39, and allowing the turnstile to be rotated by sliding pressure being applied by the patron. The next person required to deal with the teller will enter one of the vacant compartments and applying hand pressure on one of the radiating walls 21, 22 or 23, will rotate the turnstile until 110 his compartment registers with the cashier's wicket. The cashier then releases the lever 36 and allows the bolt 30 to lock the turnstile in its present position.

It is obvious that as soon as the bolt 30 115 has been withdrawn, and the turnstile rotated past the projection 43, the cashier can release the pedal 38 with the lever 36 since the bolt will be automatically held in retracted position by the L-shaped lever 40 as 120 previously described.

From the foregoing the operation of my 125 improved system of bank protection against bandits will be readily understood. The customer wishing to transact business enters 130

the bank and has business, for instance, with the cashier. He at once enters the only compartment in the turnstile which is open to him. Of the other compartments, one 5 being open to the cashier and the entrance to the other closed by the supplementary wall. The cashier then presses the push button at his foot and the turnstile is rotated by the customer, bringing the compartment 10 with the customer opposite the cashier's cage, where it is automatically held in locked position. The customer then transacts his business and on it being satisfactorily completed, the cashier again presses the push pin at his foot and allows the turnstile to move forward until the next compartment 15 is opposite the cage, when it is again locked, and so on.

As many changes could be made in the 20 above construction and many apparently widely different embodiments of my invention, within the scope of the claim, constructed without departing from the spirit or scope thereof, it is intended that all mat-

ter contained in the accompanying specification and drawings shall be interpreted as illustrative and not in a limiting sense.

What I claim as my invention is:

In a device of the character described and in combination with a turnstile having engaging means thereon, a spring-actuated locking bolt adapted in normal position to selectively engage with said engaging means and means for operating the bolt from a distance to unlock it, a pivotally mounted gravity operable dog, provided with unequally weighted arms, associated with said bolt and adapted normally to retain the bolt in withdrawn or unlocked position, and means associated with the turnstile adapted on the rotation of the latter to selectively contact with said dog to operate it from normal position to automatically release the spring actuated bolt at predetermined points in the travel of the turnstile.

In witness whereof I have hereunto set my hand.

EZRA JUDSON BUCKNAM.
